(57) **CLAIM**

The ornamental design for a furniture component, as shown
and described.

DESCRIPTION

FIG. 1 is a front elevational view of a furniture component
incorporating my new design.

FIG. 2 is a right-side elevational view thereof; and,

FIG. 3 is a top plan view thereof.

The rear and left-side elevational views are identical to
FIGS. 1 and 2, respectively.

The bottom plan view is identical to FIG. 3.
